UNITED STATES PATENT OFFICE.

EARL E. BELLOIR, OF BLACK DIAMOND, WASHINGTON.

CAR-WASHING DEVICE.

Application filed May 15, 1925, Serial No. 30,576. Renewed May 1, 1926.

This invention relates to hand washing devices designed more particularly for use in connection with the cleaning of motor vehicles or the like, and constructed with a view to permitting the operator to readily control the flow of washing fluid during the application of the same, with the applying means constructed to readily and evenly distribute the washing fluid over the surface being cleaned.

The invention is illustrated in the accompanying drawings in which:—

Figure 1 is a view in elevation with parts in section of the improved hand washing device.

Figure 2 is a detail elevation of the receptacle.

The improved hand washing implement comprises a receptacle 1 preferably of bag form and more or less resilient or yielding, such for example as would follow the construction of a receptacle of rubber, leather or the like. The receptacle is in the form of a hot water bottle and the wall 2 thereof is formed with a series of apertures 4 of comparatively small diameter to permit the cleansing fluid to flow from the interior of the receptacle to the exterior in a plurality of streams.

The interior of the receptacle is formed with a plurality of longitudinally extending ribs 3 which extend inwardly from the wall and serve to prevent the complete collapse of the receptacle under any possible pressure in its use as a washing implement.

The outer surface of the receptacle is formed with a series of ribs 5 and an absorbent material such as a sponge or cloth 6 is arranged about the exterior of the receptacle overlying the ribs 5.

The receptacle is formed with an inlet 7 at one end with which communicates a conveying tube 8 having a restricted passage 9 in a portion thereof, the flow of fluid 45 through which is controlled by the valve 10

operable by the stem 11 projecting exteriorly of the tube and adapted for manual control. The tube 8 is provided with a loop 12 of the size to fit over the arm of the user, so that the cleaning implement may be suspended adjacent to his hand for convenient grasping when desired. The tube 8 is preferably connected through the universal coupling 13 to which leads a supply tube 14 preferably of greater diameter than the tube 8.

In use, the operator by grasping the implement either directly or through the medium of the flexible handle 15 connected thereto controls the valve 10 to admit water or other cleansing fluid to the receptacle to the desired extent. This fluid finding its way through the openings in the wall of the receptacle saturates the absorbent material and permits the application of the fluid to the surface to be cleaned in a ready, convenient and even manner. It is of course apparent that through the control of the flow of the fluid the operator may arrange the washing action and fluid therefor to suit conditions of the surface to be cleaned, and as the receptacle as a whole is readily yielding, it is apparent that obstructions on the surface being cleaned will be fully and completely reached without liability of marring or scratching.

What is claimed as new is:—

A hand washing implement including a flexible container formed with perforations, ribs arranged interiorly of the container to prevent complete collapse of the receptacle, ribs arranged exteriorly of the container, absorbent material overlying the said ribs and having holding cooperation therewith, a source of supply of washing fluid, and means for controlling the supply of washing fluid to the interior of the container.

In testimony whereof I affix my signature.

EARL E. BELLOIR.
